AUTOMATIC STARTING MECHANISM

Paul Maurer, Clifton, N. J., assignor to Eclipse
Machine Company, Elmira, N. Y., a corporation
of New York

Application May 28, 1932, Serial No. 614,221

10 Claims. (Cl. 290—37)

This invention relates to automatic starting mechanism for internal combustion engines and more particularly to controlling devices for preventing closure of a starting switch while the engine is running and causing closure thereof in case of engine stall.

In automatic starting mechanism of the type employing a control relay energized from an engine driven generator to hold the starting switch open during self-operation of the engine, it is of course desirable that the action of the relay be uniform and reliable. That is, the relay should hold the starting circuit open during the lowest idling speeds of the engine, but should release uniformly when the engine stops.

It has been found that in order for the relay to hold open under the influence of the feeble current supplied by the generator at idling speeds, or supplied by the starting motor when the armature thereof is spinning by momentum in its residual field, the magnetic circuit of the relay should be substantially closed. On the other hand, however, when the relay armature is allowed to contact its pole piece, a residual flux is maintained in the magnetic circuit thus closed, which may in some cases prevent the release of the relay when the exciting current drops to zero.

Moreover, when the armature of the relay is allowed to contact the pole piece, the releasing action of the relay is affected by the area of the surfaces in contact, and variations of this area due to inaccuracies in formation of the parts or wear in service may materially alter the characteristics of the relay.

It is an object of the present invention to provide a novel control relay for automatic starting mechanism which is uniform and reliable in operation irrespective of reasonable tolerances in manufacture and wear in service.

It is another object to provide such a device embodying means for accurately and permanently adjusting the sensitivity and electro-magnetic balance of the relay.

It is a further object to provide such a device in which the adjusting means may readily be set to compensate for variations in the characteristics of the individual automatic starting device.

It is another object to provide such a device embodying an arrangement whereby magnetic sticking of the relay is effectively prevented.

It is another object to provide such a device in which the electro-magnetic balance of the relay is under the control of a manually operable member such as the ignition switch of the engine

whereby opening of such switch causes the relay to be biased toward idle position.

Further objects and advantages will be apparent to those skilled in this art from the following description taken in connection with the accompanying drawing in which:

Fig. 1 is a semi-diagrammatic showing of a preferred embodiment of the invention;

Fig. 2 is an enlarged detail partly in longitudinal section showing one method of spacing the relay armature from its pole piece; and

Fig. 3 is a view similar to Fig. 2 showing a slightly different arrangement with respect to the spacing means.

Referring to Fig. 1 of the drawing, there is illustrated a battery 1 grounded at 2 and connected by a lead 3 to a magnetic starting switch indicated generally at 4. The starting switch is connected through a single turn coil 5 and lead 6 to a starting motor SM which is grounded at 7 to complete the starting circuit.

A solenoid 8 is provided for closing the starting switch 4, and is energized from the battery 1 by means of a control circuit including battery lead 3, ignition switch 9, lead 11, lead 12, fixed contact 13 and movable contact 14 which is mounted on a spring strip 15 grounded at 16 to complete the control circuit.

Contact 14 is normally in engagement with contact 13 but is arranged to be moved out of engagement therewith by means of a pivoted lever 17 which is moved by a magnetic plunger 18 so as to engage a weight member 19 on the end of the spring strip 15 and bend said strip backward to break contacts 14, 15. Plunger 18 is normally biased toward its upper position as illustrated by yielding means such as a spring 21 and is retracted into position to open contacts 13, 14 when the engine starts by a solenoid 22 having a fixed pole piece 20. Solenoid 22 is connected at one end by a lead 23 to the starting motor side of the starting switch 4 and is grounded at its opposite end as indicated at 24. Coil 22 also

serves to maintain the plunger 18 in its retracted or switch-open position as defined by the pole piece 20, by virtue of current generated by the starting motor when spinning by momentum whereby reclosure of the contacts is prevented until the starting motor comes substantially to rest.

Means are provided for maintaining the plunger 18 retracted during the self-operation of the engine in the form of a solenoid 25 connected at one end by a lead 26 to an engine driven

generator G, and also grounded at its opposite end at 24.

In commercial devices of this character, some difficulty has been encountered in securing entirely uniform action of the relay under the control of the feeble currents generated by the starting motor during spinning and by the generator during slow idling of the engine. In other words, relays which are arranged to unfailingly be held down by these feeble currents are usually constructed with substantially closed magnetic circuits and therefore occasionally fail to release when the currents cease altogether, by reason of the residual flux in the magnetic circuit of the relay; whereas if the springs 21 are made sufficiently stiff to unfailingly release the relay, the relay may fail to be held down during motor spin or during very slow idling of the engine. Moreover, it has been found that the characteristics of the relay with respect to these functions may vary somewhat due to inaccuracies in the formation of the contacting surfaces of the armature 18 and pole piece 20, and due to wear of these surfaces in prolonged service.

It has been found, however, that if the armature 18 is prevented from making direct contact with the pole piece 20, the effect of such inaccuracies or wear is reduced, and the action of the relay is uniform and dependable. Obviously, however, if there be a non-magnetic gap between the armature and pole piece, more ampere turns are required to secure the flux necessary to hold the armature 18 in its retracted position.

According to the present invention, the problems here presented are solved by interposing a non-magnetic spacing means in the form of a disc 27 between the armature 18 and the pole piece 20, and supplying a source of additional ampere turns in the form of a third solenoid 28, the magneto-motive force of which is adjustable in order to compensate for the additional reluctance in the magnetic circuit of the relay caused by the spacing means 27. As here shown this is accomplished by connecting the solenoid 28 to the battery 1 through the ignition switch 9, lead 29, variable resistance 31 and lead 32, the solenoid being grounded at 24 to complete the auxiliary circuit.

It will be understood that the thickness of the spacing means 27 has been exaggerated in the drawing inasmuch as the actual thickness thereof would be a matter of a few thousandths of an inch only. This spacing means may be formed in any suitable way, as for instance by plating the end of the armature or of the pole piece or both, or as illustrated in Figs. 2 and 3 it may be formed as a separate disc inserted loosely in the core 33 of the relay.

As illustrated in Fig. 2, the core 33 is provided with a shoulder 34 adapted to limit the upward movement of the spacing disc 27, and the armature 18 is slightly reduced in diameter from the diameter of the pole piece 20. As shown in Fig. 3, a shoulder 35 is rolled in the core 33 for the same purpose and the armature 18 is provided with a slightly reduced extension for engaging the spacing member 27.

In adjusting the device for use, suitable values are selected for limiting values of current traversing the holding coils 22 and 25 below which limits the relay must release and above which limits the relay must be retained in running position. The coils are thereupon energized selectively by currents of the limiting values and the resistance 31 is adjusted to vary the flux through

the auxiliary coil 28 until release of the relay takes place at approximately the mean of the limiting values for the holding coils. It will be readily seen that this adjustment of the auxiliary coil takes care of any individual variations in the magnetic characteristics of the box, in the dimensions or windings of the coils, or in the dimensions of the armature, pole piece or spacing disc. Inasmuch as the spacing disc maintains the armature 17 spaced a uniform distance from the pole piece 20 when the relay is energized, the magnetic balance of the relay will as above pointed out be maintained within close limits through long periods of service. If, however, the magnetic balance should be disturbed in any way, the resistance 31 may readily be adjusted to once more secure the desired balance.

It will be understood further that it may be desirable to vary the characteristics of the relay in accordance with the electrical characteristics of various installations. That is, the electrical characteristics of the starting motor and of the generator may vary considerably, and the coil 28 with the variable resistance 31 offers a convenient and positive method of obtaining the optimum relationship between the relay and the particular installation in which it is intended to be used.

In the operation of the device, closure of the ignition switch 9 causes energization of the solenoid 8 inasmuch as contacts 13 and 14 are normally closed. At the same time, the auxiliary coil 28 is energized, but the flux produced thereby is of course much too small to have a perceptible effect on the armature 18. When the starting switch 4 is closed by solenoid 8, the starting circuit is closed and the starting motor is energized to crank the engine. At the same time, the motor shunt coil 22 is energized through the lead 23, but the flux produced thereby is opposed by the single turn coil 5 which retains the armature 18 in its upper position as long as the coil 5 is traversed by the heavy cranking current.

When the engine starts, the reduction in current flow through the series coil 5 and the concomitant rise in voltage across the shunt coil 22 enables the shunt coil to overcome the series coil and attract the armature 18 against the pole piece 20. Contacts 13, 14 are opened thereby, deenergizing solenoid 8 and causing the starting switch 4 to open. Shunt coil 22 is thereby cut off from the battery 1 but is still energized to a small extent by current generated by the spinning of the armature of the starting motor in its residual field. This flux through coil 22, assisted by the flux in the auxiliary coil 28 is sufficient to retain the armature 18 in its attracted position until the starting motor comes substantially to rest.

When the engine starts the generator G 1 driven thereby picks up and energizes the generator coil 25 to retain the armature 18 in its attracted position as long as the engine is self-operative. It will be understood that during slow idling the flux from the generator coil 25 may fall to a very low value, but as above pointed out, the auxiliary coil 28 is so adjusted as to assist coil 25 sufficiently to retain the armature 18 as long as the engine is self-operative.

It has been found that the sensitivity of the relay as secured by the balance between the spring 21 and auxiliary coil 28 is such that there has been no difficulty in securing the desired operating characteristics. It has further been found that these operating characteristics are more uniform and are retained more perma-

nently than in those cases where the armature is allowed to make direct contact with its pole piece.

Although but one embodiment of the invention has been shown and described in detail, it will be understood that other embodiments are possible and various changes may be made in the design and arrangements of the parts without departing from the spirit of the invention as defined in the claims appended hereto.

10 What is claimed is:—

1. In an automatic starting mechanism for internal combustion engines, a starting switch, a control relay therefor having an armature normally biased to idle position, magnetic means for attracting and holding said armature while the engine is self-operative, and adjustable electromagnetic means under the control of the operator for supplementing the residual magnetic holding effect of the holding means and opposing the 15 normal biasing of the armature when in attracted position.

2. In an automatic starting mechanism for internal combustion engines, a starting switch, a control relay therefor having an armature normally biased to idle position, magnetic means for attracting and holding said armature while the engine is self-operative, and adjustable electromagnetic means for supplying a constant magnetic flux to assist the residual magnetic holding 20 effect of said holding means.

3. In an automatic starting mechanism for internal combustion engines, a starting switch, a control relay therefor having a fixed pole piece and an armature normally biased to idle position, magnetic means responsive to rotation of the engine for attracting and holding said armature during self-operation of the engine, means providing a non-magnetic gap between said pole piece and armature, and adjustable electromagnetic means under the control of the operator for producing a magnetic flux in a holding direction for the armature to assist the residual magnetic holding effect of said holding means.

4. In an automatic starting mechanism for internal combustion engines, a starting switch, a control relay therefor having an armature normally biased to idle position, magnetic means for moving said armature to running position when the engine starts and for holding the armature in running position responsive to self-operation of the engine, and electromagnetic means for supplying a constant magnetic flux supplementing the residual magnetic holding effect of the holding means to retain the armature in running position.

5. In an automatic starting mechanism for internal combustion engines, a starting switch, a control relay therefor, electromagnetic means for retaining said relay in position to prevent closure of the starting switch while the engine is self-operative, and adjustable electromagnetic means under the control of the operator for supplementing the residual magnetic holding effect of said retaining means by a substantially constant force which is insufficient by itself to retain said relay in switch open position.

6. In an electrical system for internal combustion engines, a starting system including a battery and a starting motor, an engine driven generator, a magnetic starting switch, a control relay for said starting switch including a movable armature and a pole piece, means for holding

said armature against the pole piece during self-operation of the engine, nonmagnetic means for spacing the armature from the pole piece, and adjustable means for setting up a substantially constant magnetic-motive force through the relay supplementing the residual magnetic holding effect of said holding means to compensate for the reluctance caused by said spacing means.

7. In an electrical system for internal combustion engines, a starting system including a battery and a starting motor, an engine driven generator, a control relay for said starting motor including a movable armature and a pole piece, a coil energized by rotation of the starting motor for holding the armature against the pole piece during spinning of the starting motor, a coil energized by rotation of the generator for holding the armature against the pole piece during self-operation of the engine, a third coil energized from said battery to exert a supplemental holding effect on the armature, and means for adjusting the flux of the third coil to secure uniformity of control of the relay by the first and second coils.

8. In an electrical system for internal combustion engines, a starting system including a battery and a starting motor, an engine driven generator, a control relay for said starting motor including a movable armature and a pole piece, a coil energized by rotation of the starting motor for holding the armature against the pole piece during spinning of the starting motor, a coil energized by rotation of the generator for holding the armature against the pole piece during self-operation of the engine, non-magnetic means for spacing the armature from the pole piece, a third coil energized from said battery to exert a supplemental holding effect on the armature, and means for adjusting the flux of the third coil to compensate for the reduction in sensitivity of the relay caused by said spacing means and to secure uniformity of control of the relay by the first and second coils.

9. In an automatic starter control for internal combustion engines a magnetic starting switch, a control circuit therefor including an electromagnetic relay, means for biasing said relay to switch closing position, said relay including electromagnetic means responsive to a running function of the engine for holding said relay in switch open position, additional electromagnetic means for supplementing the holding effect of said holding means in opposing said biasing means, and manually operable means for energizing and deenergizing said additional means.

10. In an automatic starter control for internal combustion engines a magnetic starting switch, a control circuit therefor including an electromagnetic relay, means for biasing said relay to switch closing position, said relay including electromagnetic means responsive to a running function of the engine for holding said relay in switch open position, additional electromagnetic means for supplementing the holding effect of said holding means whereby it is necessary for said biasing means to overcome both the residual holding effect of the holding means and the holding effect of the supplemental means in order to move the relay to switch open position, and means whereby the energization of said supplemental means is controlled by the ignition switch of the engine to be started.

PAUL MAURER.
